LAND MARKER

Paul L. Rapp, Toledo, Ohio

Application July 13, 1951, Serial No. 236,656

1. Claim. (Cl. 189—21.3)

This invention relates to monuments or markers and has particular reference to a device for use by surveyors or the like in marking transit and control points in pavements. This application is a continuation-in-part of copending application Serial No. 687,128, filed July 30, 1946, now abandoned.

Among the objects of the invention is to facilitate the accuracy and long life of markers of this type where successive layers of wearing surface material are to be deposited upon a permanent base, as for instance where base structures of concrete are to be periodically covered with a wearing surface of bituminous material or so-called "black top" for purposes of maintenance and repair.

Other objects of the invention are simplification of installation while insuring permanency and accuracy over a long period of time. An important specific objective is to firmly anchor the base or bed of the actual marking element and at the same time so arrange the latter in the bed that it is permitted relatively wide displacement in a vertical direction while remaining in fixed position horizontally with reference to the bed, and to retain the marking element at a fixed level although displaceable by positive manipulation to compensate for successive surfacing layers.

Reduction in manufacturing costs and the number of separate parts requisite for accomplishing these desirable ends are among further objects of the invention, as are simplification and standardization of parts to facilitate replacements where necessary.

Various other objects and meritorious features of the invention will be apparent from the following description taken in conjunction with the drawing, wherein like numerals refer to like parts throughout the several figures, and wherein:

Fig. 1 is a side elevation, partly in section, of a complete installation;

Fig. 2 is an enlarged sectional elevation of the upper end of the device;

Fig. 3 is a top plan view thereof;

Fig. 4 is a side elevation, partly in section, of a complete installation of a modified form of the invention;

Fig. 5 is a section along 5—5 of Fig. 4;

Fig. 6 is an enlarged sectional elevation of the upper end of the assembly showing the use of adapter washers;

Fig. 7 is a top plan view of the assembly shown in Fig. 6; and

Fig. 8 is a plan view of an adapter washer.

This improved arrangement is the essence of simplicity compatible with the various objects sought and comprises a base member 10, a marking element or core rod 12, and an anchor member 14. It is of extreme importance in devices of this kind that the marking element be firmly positioned against lateral movement and against accidental or deliberate unauthorized withdrawal from the location in which it is set. It is also of great importance, particularly where used as a marker on land over which successive wearing surfaces may be applied from time to time, that the marking element per se be vertically displaceable with minimum effort and disarrangement of the assembly as a whole. It is important also that the marking element be held against vertical displacement from accidental causes.

For purposes of illustration I have disclosed base member 10 in the form of a metal casting, preferably brass, in tubular form and having a wall of substantial thickness for purposes which will be brought out more clearly hereinafter. The base 10 is internally threaded at one end as indicated at 16 to receive externally threaded rod 12 which constitutes the marking member per se. It should be noted that the rod 12 is of uniform diameter throughout its length and constitutes a true cylinder with the exception of the surface threading.

The anchor 14 is preferably in the form of an ordinary pipe threaded into the lower portion of base member 10 and from four to six times as long as the base member. Rod 12 may be of substantially the same axial length as the base member 10 and the internal threading of said base member for reception of the rod need extend only a portion of the axial length of the base in order to accomplish its intended function.

It will be apparent as the description proceeds that the rod 12 or marking member per se will always when in use project somewhat above the upper end of the base 10. For that reason the base 10 and rod 12 may be of substantially the same axial dimensions while at the same time providing sufficient threading at the lower end of the base for adequate engagement with the threaded upper end of the anchor 14. The face of the upper, or exposed end of rod 12 is provided with one or more slots, here shown in the form of transverse slots 18 and 20, by which the rod may be rotated with the aid of a screw-driver or some other suitable tool.

Referring now more particularly to Fig. 1,

wherein the device has been illustrated as installed for use in the manner particularly contemplated, the numeral 22 represents concrete paving in which the base 10 and anchor 14 are embedded. Specifically, I have found that for this particular purpose a rough-finish brass casting of about four inches in axial length and a wall thickness of about three-eighths of an inch constitutes a satisfactory base for reception of a one-inch brass rod approximately four inches long and provided with eight threads to the inch. The anchor pipe 14 is preferably about two feet long for the installation illustrated and may be a conventional one-inch pipe for reception of which the lower end of base 10 is provided with a standard one-inch pipe thread. Where the concrete paving 22 is of insufficient thickness to receive both base 10 and anchor 14, a special anchoring cavity may be dug and filled with concrete for reception of and embedding the assembly.

As hitherto suggested, the rod 12 will be adjusted to project vertically beyond the upper end of the base 10 a distance corresponding substantially to the thickness of the surfacing material 24 which is to be deposited on the concrete. By reason of the thickness of the wall of base 10 the surfacing material 24, which is packed tightly about the projecting portion of rod 12 and overies the upper end of the base, provides an additional anchor against displacement of the under surface portion of the marker assembly. The fact that the surfacing material 24 is packed about the wall of the projecting portion of rod 12 and into the threads thereof precludes any possibility of accidental rotative movement of rod 12 and consequently any accidental vertical displacement thereof with reference to the surface. However, the resistance to rotation of rod 12 offered by the packed surfacing material 24 is insufficient to hamper ready manipulation of the rod by positive action when it becomes necessary to raise the level thereof to compensate for the next additional layer of surfacing material. This improved assembly affords the additional advantage of embodying a main anchor element 14 disposed a sufficient distance below the wearing surface 24 to substantially preclude damage resulting from road shock, excessive pounding, or accidental impacts. Furthermore, should the upper portion of the assembly comprising base 10 and marker 12 be damaged, these latter two elements may very easily be replaced by simply threading a substitute base, carrying a marker, over the upper threaded end of anchor 14.

The modified arrangement illustrated in Figs. 4-8 represents an improvement over the hitherto described embodiment of the invention in that its adaptability to various thicknesses of surfacing is greater and the rigidity of the assembly is increased substantially. The iron pipe constituting anchor member 30 corresponds in every way to anchor member 14 described with reference to the embodiment illustrated in Figs. 1-3. Base member 32 is preferably made of brass and of hexagonal or some other non-circular cross-sectional contour. The non-circularity of the margin assist in preventing minute rotation of the base over a long period of time, which rotation might be permitted by loosening of the material in which the base is sunk and caused by constant tremors developed as vehicles move over the surface.

Base member 32 is provided with a threaded internal bore 34 extending axially therethrough

and adapted to receive the adjustable core member 36 which is threaded externally for reception into the threaded bore of the base.

One end of the base 32 is countersunk concentrically with reference to bore 34 as indicated at 38 and the wall of the countersink is threaded for reception of the threaded upper end 40 of anchor member 30.

By virtue of the countersink 38 in base 32, core 36 may be received telescopically into the anchor pipe 30, as clearly shown in Fig. 5. The internal diameter of anchor pipe 30 is sufficient for this purpose, but the clearance provided, which is indicated at 42, is relatively small. I have found that a surrounding clearance of approximately one sixteenth of an inch is eminently suited to obtain satisfactory results.

In Fig. 5 the core 36 and base member 32 have been set to lie in the plane of an initial surfacing 44 of concrete or other material such as asphalt. When, on resurfacing, an additional thickness 46 of material is superimposed over the original surfacing, the survey point is maintained by threading core 36 upwardly to the plane of the new surface, as indicated clearly in Fig. 6. Washers 48, 50 and 52 of suitable different thicknesses may be provided for threading over the previously elevated upper end of core 36, thus in effect extending the base member 32 upwardly to the surface of the newly laid material.

The upper or exposed end of core 36 is provided with means lying within its confines, such as radial slots 54, for reception of a tool to rotate the core to adjusted position. The washers 48, 50 and 52 are preferably provided with oppositely disposed depressions 56 and 58 for reception of a spanner wrench or similar tool adapted to thread the washers over the core. While in the modification disclosed in Figs. 4-8 a single radial slot 54 only is disclosed, crossed radial slots of the type described in conjunction with Figs. 1-3 are preferred, since the point of intersection of such slots provides a centrally disposed depression adapted for use in conjunction with a centering tool when the monument is being set.

The arrangement described in conjunction with Figs. 4-8 is particularly desirable in view of its compactness and extreme limit of extensibility. By virtue of the fact that the core 36 telescopes into the tubular body of anchor pipe 30, such core may be of any desired length without limitation by way of the axial length of the bore in the base 32. The structure permitting this maximum extensibility also obtains a maximum rigidity by reason of the fact that the outside diameter of core member 36 and the inside diameter of anchor pipe or member 30 are such as to provide a relatively small circumferential clearance, preferably no more than about a sixteenth of an inch. Due to this small clearance, any tendency of the core 36 and/or its base member 32 to move out of vertical alignment with the embedded anchor member 30 is resisted as the telescoped lower end of the core 36 abuts the inside wall of anchor member 30. Thus the arrangement obtains maximum rigidity both in and out of use.

While certain preferred embodiments of the invention have been described, various modifications will be apparent and for that reason I wish to limit myself only within the scope of the appended claim.

I claim:

A land marker comprising an internally threaded tubular base member embedded in the surface of a roadway, a threaded countersink on

the lower end of the bore of said base member, an elongated tubular anchor threaded at its upper end and coupled to the threads in said countersink, the internal diameter of said tubular anchor being greater than the internal diameter of said bore, and a threaded core having an axial length greater than said base adjustably threaded into said bore and extending from the end thereof into said tubular anchor with sufficient clearance therebetween to permit some lateral flexibility.
